UNITED STATES PATENT OFFICE.

JOSEPH SIPOZ, OF MICHEL, CANADA.

COMBINED SPOOL AND NEEDLE CASE.

No. 826,372.

Specification of Letters Patent.

Patented July 17, 1906.

Application filed October 19, 1905. Serial No. 288,516.

To all whom it may concern:

Be it known that I, JOSEPH SIPOZ, a subject of the Emperor of Austria-Hungary, residing at Michel, in the Province of British Columbia and Dominion of Canada, have invented new and useful Improvements in a Combined Spool and Needle Case, of which the following is a specification.

My invention relates to a combined spool and needle case; and its primary object is to provide a novel and highly useful device of this character upon which may be wound two or more threads of different colors and which is adapted to receive one or more needles and prevent them from rusting, the same being so constructed that the needles may be readily and quickly removed therefrom and replaced therein.

A further object of the invention is to provide a device of this character which is simple and durable of construction, which may be manufactured and sold at a comparatively low cost, and which is admirably adapted for the purposes for which it is intended.

With the above and other objects in view the invention consists in the construction, combination, and arrangement of parts hereinafter fully described, claimed, and illustrated in the accompanying drawings, where-

in— Figure 1 is a side elevation of the combined spool and needle case constructed in accordance with my invention. Fig. 2 is a vertical central sectional view thereof. Fig. 3 is a top plan view thereof. Fig. 4 is a view similar to Fig. 3, the cap being removed; and Fig. 5 is a detail perspective view of the cap and the cushion carried thereby for the reception of the pointed ends of the needles.

Referring to the drawings by reference-numerals, I designates a spool, the same being provided with two or more winding-faces 2, whereby the spool is adapted for the reception of two or more threads of different colors.

The spool is provided with a centrally-located passage 3, the same terminating at a point adjacent one end of the spool, whereby to provide the passage with a closed end 4, the other end thereof being fully open, as fully illustrated in Figs. 2 and 4 of the drawings. This passage is adapted for the reception of

the needles, and it may be used to support the spool upon a sewing-machine in the usual manner, the closed end thereof not interfering with the application of the same to the machine. One end of the spool is provided with an annular recess 4^a, the same being arranged concentrically with relation to the passage 3 and adapted for the reception of the lower end of a flange 5 of a cap 6, through the medium of which the passage 3 may be closed to render the same moisture-proof. The cap 6 is provided with a milled edge 7, whereby to facilitate the application and removal of the same, and it is also provided with a cushion-filling 8. The cushion-filling 8 may be constructed of cork, paper, or any other material which may be easily penetrated, as the same is adapted for the reception of the pointed ends of the needles. The lower portion of the cushion-filling 8 is reduced to project into the open end of the passage 3 to provide, in effect, a packing for rendering the passage 3 moisture-proof.

The needles are secured to the cushion-filling 8 of the cap 6 by inserting their pointed ends therein, after which the cap is applied to close the passage 3 and suspend the needles therewithin. When it is desired to use a needle, the cap is removed and a needle may be removed therefrom easily and quickly.

It is apparent from the above description, taken in connection with the accompanying drawings, that I provide a combined spool and needle case which may contain two or more threads of different colors, thereby admirably adapting the same for the use of those who are not provided with a complete sewing set and by means of which needles may be conveniently carried and prevented from rusting and from which the needles may be readily and quickly removed.

Changes in the form, proportions, and minor details of construction may be made within the scope of the invention without departing from the spirit or sacrificing any of the advantages thereof.

Having fully described and illustrated my invention, what I claim is—

A device of the character described, comprising a spool having a passage closed at one end and open at its other end, said spool be-

ing provided with an annular recess arranged concentrically with relation to the passage, a cap adapted to seal said passage and having the edge of its flange disposed within said recess, and a cushion-filling for the cap, said cushion-filling being adapted to receive needles.

In testimony whereof I affix my signature in presence of two witnesses.

JOSEPH SIPOZ.
